US00D847857S

(12) **United States Design Patent** (10) **Patent No.:** **US D847,857 S**
(45) **Date of Patent:** **** May 7, 2019**

(54) **DISPLAY SCREEN OR PORTION THEREOF WITH ICON**

(71) Applicant: **Agile Transformation, Inc.**, Omaha, NE (US)

(72) Inventor: **Sally Elatta**, Omaha, NE (US)

(73) Assignee: **Agile Transformation, Inc.**, Omaha, NE (US)

(**) Term: **15 Years**

(21) Appl. No.: **29/663,964**

(22) Filed: **Sep. 20, 2018**

Related U.S. Application Data

(63) Continuation-in-part of application No. 29/626,750, filed on Nov. 20, 2017, now Pat. No. Des. 806,120, which is a continuation of application No. 29/582,748, filed on Oct. 31, 2016, now Pat. No. Des. 806,120.
